(57) **CLAIM**

The ornamental design for a shotgun, as shown and described.

DESCRIPTION

FIG. 1 is a rear elevational view, showing my new design; FIG. 2 is a bottom plan view thereof; FIG. 3 is a top plan view thereof; FIG. 4 is a front elevational view thereof; FIG. 5 is a left side elevational view thereof; FIG. 6 is a perspective view thereof; FIG. 7 is a right side elevational view thereof; FIG. 8 is a partial right side elevational view, on a larger scale, thereof; and, FIG. 9 is another partial right side elevational view, on a larger scale, thereof.

The portion of the shotgun shown in broken lines forms no part of the design claimed.
